UNITED STATES PATENT OFFICE.

GEORGE E. SMITH, OF OIL CITY, LOUISIANA.

FOLDING CAR STEP.

Application filed January 19, 1924. Serial No. 687,260.

To all whom it may concern:

Be it known that I, GEORGE E. SMITH, a citizen of the United States, residing at Oil City, in the parish of Caddo and State 5 of Louisiana, have invented a new and useful Folding Car Step, of which the following is a specification.

This invention relates to folding car steps and the object thereof is to provide novel 10 means for raising and lowering the step attached to the stationary steps of the car and so constructed that it may be readily folded to lie under the lowermost stationary step and present no obstruction when not in 15 use and which may be quickly and easily projected for use when desired.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed without departing from the spirit of the invention.

In the accompanying drawings:

Figure 1 represents a side elevation of a flight of car steps with this improved extension step shown applied and in extended operative position in full lines, it being shown folded in dotted lines.

Fig. 2 is a detail perspective view showing the extension step and its connecting parts.

Fig. 3 is a longitudinal section taken on the line 3—3 of Fig. 2.

Fig. 4 is a detail transverse section taken on the line 4—4 of Fig. 1; and

Fig. 5 is a transverse section taken on the line 5—5 of Fig. 1.

In the embodiment illustrated a flight of stationary steps 1 are shown depending from and supported by the usual car platform 2. The extension step which is supported by the lowermost step or tread of the flight 1 comprises a riser 10 here shown formed of metal with side flanges 11 and 12 between which is located the tread member 20 of the extension step composed of wood or other suitable material mounted on a base plate 21 having upstanding side flanges 22 which fit within the flanges 11 and 12 of the riser and are pivotally connected to the lower ends thereof as shown at 23. The riser is pivotally mounted at its upper end beneath the stationary steps a pintle 13 being here shown

for connecting this extension step with the stationary step. Foldably connected links 14 and 15 connect the front portion of tread 20 with the upper portion of riser 10 and similar links 14^a and 15^a connect the other side of these members so that the tread 20 may fold against the outer face of riser 10 and these parts when so folded may be folded back under the lowermost tread of the stationary steps as shown in dotted lines in Fig. 1.

A bar 16 is pivotally connected with the front end of tread 20 at one side thereof and is mounted to slide in a track 19 carried by the outer face of a plate or bar 17 supported by the stationary steps at one side thereof. This track or guide 19 is shown with in-turned flanges 19^a on its outer face between which the slide 16 is designed to reciprocate 75 for retracting and extending the folding step.

The plate 17 has a bead 17^a along its upper edge which is notched as shown at 18 for adjustable engagement by a spring pressed pawl 24 carried by a bell crank lever 25 which is fulcrumed on an arm 26 projecting upwardly from a head 27 fixedly secured to the outer face of the slide 16. The arm 26 is equipped with a hand grip 28 for moving the head 27 and the slide fixed thereto longitudinally along the track 19 for projecting and retracting the folding step, it being of course understood that the lever 25 is depressed to release the pawl 24 from the rack formed by the notches 18.

In the use of this extension step when the parts are in the position shown in full lines in Fig. 1 and it is desired to fold up the extension step the hand grip 28 is 95 grasped and an upward pull exerted thereon which causes the slide 16 to move upwardly in the track 19 carrying with it the tread 20 which folds up against the riser 10 the links 14 and 15 and 14^a and 15^a breaking joint when such pull is exerted to permit the step to fold into the dotted line position shown in Fig. 1. During this upward movement of the slide 16 the dog or pawl 24 rides up on the bead 17^a over the notches 18 until the extension step has been completely housed under the stationary steps when the lever 25 under the action of its spring 30 will force the pawl into locking engagement with one of the notches 18 and thus securely hold the extension step in folded inoperative position.

When it is desired to project the extension step into the full line position shown in Fig. 1 the operation above described is reversed, the pawl 24 being released from its notch 18 by grasping lever 25 and moving it toward the hand grip 28. The hand grip with the head 27 carried thereby is then moved downwardly carrying with it the slide 16 which operates to move downwardly and outwardly the tread 20 of the extension step opening up the links which connect it with riser 10 until it assumes the position shown in Figs. 1 and 2. The links 14 and 15 and 14^a and 15^a are constructed at their joints as shown in Fig. 3 one having a tongue 31 on its lower inner edge which engages a shoulder 32 of the other link and thus forms a stop for limiting the opening movement of the links.

From the above description it will be seen that this extension step may be very quickly operated to either retract or project it and avoids the necessity of the porter carrying the usual box to assist passengers in alighting from a train.

I claim:

1. The combination with a flight of stationary steps, of a riser pivoted at its upper end to the lowermost step at the front edge thereof, a tread pivoted to the lower end of the riser, a bar pivoted to the front end of said tread and mounted to slide longitudinally at the side of the stationary steps, pivoted, folded, links connecting the front end of said tread with said stationary steps, a rack on said stationary steps, and a pawl

carried by said bar to engage said rack and lock said bar in adjusted position.

2. In an extension car step the combination with the platform steps; of a pivotally connected tread and riser, said riser being pivoted at its upper end to the front portion of the lowermost platform step, break joint links connecting the front portion of said tread with said steps, a bar pivoted to the front end of said tread, a guide on the side of the steps in which said bar is mounted to slide, an upwardly extending handle fixed to said bar, and cooperating means on said handle and steps to lock the bar in adjusted position.

3. In a device of the class described, a fixed stairway, a rack on the stairway, a guide on the stairway, a bar mounted to slide in said guide, a head carried by said bar and having a handle rising therefrom and provided with a spring pressed pawl to engage said rack and hold the bar in adjusted position, a foldable riser pivoted to the stairway and a foldable tread pivoted to the riser, the tread being connected to the bar and adapted to move into retracted and extended positions on the operation of the bar.

In testimony that I claim the foregoing as my own, I have hereto affixed my signature in the presence of two witnesses.

GEORGE E. SMITH.

Witnesses.
